VARIABLE INDUCTANCE

Richard L. Campbell, Maywood, N. J., assignor
to Allen B. Du Mont Laboratories, Inc., Passaic,
N. J., a corporation of Delaware

Application August 22, 1944, Serial No. 550,567

2 Claims. (Cl. 171—242)

1

This invention relates to an inductance coil of which the inductance can be varied very easily and can be adjusted very accurately to the desired amount.

In carrying out the invention, a tube of insulating material has a coil of wire wound upon it and this tube is slidably adjustable along and beyond a core of magnetic material onto a core of non-magnetic material so as to vary the inductance. These cores are supported by metal rods that serve as conducting members to which the ends of the coil are attached.

This inductance coil is particularly useful as a compensating coil for wide band amplifiers. In a wide band amplifier the residual or stray capacities are often a limiting factor. By this invention an extremely small yet efficient compensating coil is provided in which the stray capacity introduced into the circuit is very small.

Another object of the invention is to provide means that can be easily and quickly adjusted for providing the correct compensation in amplifier stages, using vacuum tubes.

Another object of the invention is to make use of the permeability effects of high frequency iron in order to reduce the amount of turns of wire that is required for a compensating coil, with a consequent saving in physical size and decrease in capacitance.

Another object is to minimize distributing capacitance and provide inexpensive means for varying the inductance.

The invention may be understood from the description in connection with the accompanying drawing, in which:

Fig. 1 is a longitudinal section of an illustrative embodiment of the invention;

Fig. 2 is a section along the line *a*—*a* of Fig. 1;

Fig. 3 is a section through a modification; and

Figs. 4 and 5 are side views of other modifications.

In the drawing, reference characters 1 and 2 indicate aligned metal terminal rods that are made of non-magnetic material such as copper, for example. The ends of these terminals 1 and 2 are enlarged as shown at 1' and 2' and anchored in cylinders 3 and 4 of insulating material. The cylinder 3 is made of rigid insulating material, such as Bakelite, and the cylinder 4 is made of rigid insulating material in which very small or microscopic segregated particles of powdered iron are embedded. The cylinders 3 and 4 are connected to the enlarged ends of the terminals 1 and 2 so as to be rigidly held in aligned fixed position with respect to each other.

2

A cylindrically shaped body or tube 6 of insulating material surrounds the cylinders 3 and 4 and fits tightly around them. This may be a strip of impregnated paper or other suitable insulating material wound or wrapped into a coil with the layers adhered together and mounted on the cylinders 3 and 4 to provide a form upon which the coil 7 of wire is wound.

The coil 7 of copper or other insulated fine wire 10 of conducting material is wound on the tube 6, the length of this wire being sufficient to provide the desired amount of variable inductance. The amount of inductance is determined by the positions of the tube 6 on the cylindrical bodies 4 and 5.

A strip 8 of thin insulating material such as Celluloid or mica is wound around the coil 7 and the convolutions are stuck together to provide a cylinder tightly fitting this coil.

One end of the coil 7 is connected to a flexible lead 10 consisting of several strands of fine flexible wire twisted together and being longer than the axial length of the coil 7. The other end of the lead 10 is attached to the terminal 1 by soldering, as indicated at 11. The other end of the coil 7 is attached in a similar manner by the lead 12 to the terminal 2 as indicated at 13 so that the coil 7 will not become detached from the terminals 1 and 2 as this coil is adjusted for varying the inductance. Loops 14 and 14' are provided in the connecting leads 10 and 12 to facilitate adjustment of the coil 7 longitudinally on the cylinders 3 and 4 to vary the inductance.

In the modification shown in Fig. 3 the coil 1' 35 is of much shorter axial length than the coil 7 and it is of much larger external diameter.

A strip 15 of insulating material is laid longitudinally of the tube 6 before the coil 7 is installed. After the coil 7 and cylinder 8 are in place the 40 extending end of this strip 15 is then folded back and attached to the other end thereof by cement or other adhesive material, thus forming an extending tab 16 by means of which the coil 7 is moved or adjusted along cylinders 4 and 5 to vary the inductance.

It will be obvious from the disclosure that when the central transverse plane of the coil 7 is in line with the central transverse plane of the cylinder 4 the inductance will be a maximum, and that by moving this coil by means of the tab 16 to the limit onto the cylinder 3 the inductance will be a minimum. The inductance of coils made in accordance with this invention depend 55 upon the number of turns of the wire in coil 7

and the dimensions of the parts used and the position of the coil 7.

The following is given as a specific illustrative example of a variable inductance coil made in accordance with Fig. 1 of this invention:

Fifty-six turns of 40E copper wire were wound at the rate of 260 turns per inch as a single layer coil 0.20 inch long upon a cylindrical form of insulating material 0.375 inch long. Measurements showed that the inductance of this coil ranged from 15 to 30 microhenrys and the capacitance thereof was 0.6 of a micro-microfarad

In the modification shown in Fig. 4 reference characters 21 and 22 are terminal rods or supports attached respectively to the cylinder 23 of rigid insulating material such as a phenolic compound and cylinder 24 of magnetic material such as powdered iron and a binder. A brass disc 25 is attached to the outer end of cylinder 23. The coil 27 with tab 28 is similar to the coil 7 in Fig. 1 and is mounted and moved in a way similar to the coil 7. The ends of the coil 27 are connected by flexible leads 29 and 30 to the rods 21 and 22.

In this modification the dimension and proportions are such that when the coil 27 is centered on the iron core 24 the inductance is a maximum; when it is centered on the phenolic cylinder 23 the inductance is half the maximum; and when it is centered on the brass disc 25 the inductance is one-fifth the maximum.

In the modification shown in Fig. 5, reference characters 31 and 32 are conducting supports for the solid cylinders 33 and 34. The adjacent ends of these cylinders are attached together, for example, by cementing them together. The cylinder 33 is made up of particles of conducting material 33' having some resistance, such as carbon and a binder, and an insulating shell 33''. The cylinder 34 is similar to cylinder 4, Fig. 1, and is therefore magnetic. The disc 35 attached to the outer end of cylinder 33 is metal, such as brass or copper, and is in conducting contact with this cylinder. The coil 36 is made up in a way similar to the wire coil 7 with a rigid or stiff insulating shell inside and outside of the wire coil and is provided with a tab 38 for adjusting it longitudinally. Flexible leads 39 and 39' connect the ends of coil 36 to the supports 31 and 32. A ring 40 provided with an attach-

ment lug 41 fits around the insulating shell 33'' but is removable.

In an embodiment of the invention which has proven to be satisfactory, when the coil 36 is centered upon the core 35 the inductance is a maximum, when it is centered on the cylinder 33 the inductance is half the maximum, and when it is centered upon the disc 35 it is one-fifth of the maximum.

10 When the leads 39 and 39' are connected as shown in Fig. 5 the coil 36 and resistance 33' are in parallel between the conducting supports 31 and 32. When the lead 39 is disconnected from the ring 40 the terminal 31 and lead 39 can be connected to a source of current so that the coil 36 and resistance 33' are in series.

What is claimed is:

1. An inductance, comprising a support consisting of two aligned spaced metal rods, a cylinder of insulated particles of magnetic material rigidly mounted on one of said rods, a cylinder of insulating material of the same diameter as said first named cylinder mounted on the other one of said rods, a cylindrical strip of adherent insulating material wound upon adjacent ends of said cylinders and holding them in alignment and a coil of insulated wire slidable on said cylindrical strip, said coil being substantially the length of said first named cylinder and being movable longitudinally of said cylinders and having its ends connected respectively to said metal rods.

2. The device of claim 1 in which the adjacent ends of said cylinders are in contact.
